UNITED STATES PATENT OFFICE.

CHARLES BERGERER, OF ROCHESTER, NEW YORK, ASSIGNOR TO C. T. HAM MANUFACTURING COMPANY, OF ROCHESTER, NEW YORK.

TUBULAR LANTERN.

No. 927,767.

Specification of Letters Patent.

Patented July 13, 1909.

Application filed March 30, 1909. Serial No. 486,808.

To all whom it may concern:

Be it known that I, CHARLES BERGERER, a citizen of the United States, residing at Rochester, in the county of Monroe and 5 State of New York, have invented a new and useful Improvement in Tubular Lanterns, of which the following is a specification.

This invention relates to that class of tubular lanterns which are provided with a deep 10 reflector or reflecting hood which is secured upon the oil pot and between the air tubes and which contains the burner, the globe and the plate upon which the globe rests, the globe supporting plate being so mounted 15 that it can be raised, together with the globe, within the hood for exposing the burner.

The object of this invention is to construct the lantern in such manner that the side or lift wires which connect the globe plate with 20 the vertically movable bell or canopy do not obstruct the interior of the reflector, so that the inner surface of the latter can be easily and conveniently reached for cleaning the same.

25 In the accompanying drawings, consisting of two sheets: Figure 1 is a front elevation, partly in section, of a lantern provided with these improvements and showing the parts in the position in which the globe plate rests 30 on the burner. Fig. 2 is a horizontal section in line 2—2, Fig. 1, with part of the bell broken away. Fig. 3 is a front elevation, showing the globe elevated above the burner. Fig. 4 is a side elevation, showing the parts in 35 the normal position. Fig. 5 is a fragmentary sectional view, showing a modified connection of the side wires with the globe plate.

Like reference characters refer to like parts in the several figures.

40 A represents the oil pot, B the burner, C the air tubes, D the central tube connecting with the upper ends of the air tubes, E the bell or canopy which is vertically movable on the central tube and provided with a thumb- 45 piece e, F the globe plate supporting the globe, which is shown in dotted lines, G the annular spring catch which is secured to the bell and engages the upper end of the globe, and H the handle. All of these parts are of 50 ordinary and well known construction and may be of any other suitable construction.

I represents the reflector or hood which is arranged upon the oil pot and between the air tubes and is firmly secured to these parts 55 of the lantern frame. The hood or reflector

is provided in its lower portion with an opening i through which the burner projects upwardly and in its upper portion with an opening k through which the upper portion of the globe projects and, if desired, with a 60 detachable rear portion K.

L represents the side or lift wires which are secured at their upper ends to the bell, preferably by forming both wires in one piece with a connecting bow l, Fig. 2, which is 65 beaded into the edge of the bell. These wires extend from the bell downwardly on the outer side of the reflector and have their lower ends connected with the globe plate. This connection may be made by extending 70 the lower portions m of the side wires upwardly through side openings or upright slots n in the reflector, as represented in Figs. 1-4, or by extending loops or ears o on the plate outwardly through these slots and connecting the ears with the side wires, as represented in Fig. 5. The side openings n are so long or high that they permit of the required extent of vertical movement. The connection of the side wires with the globe plate is 75 80 preferably detachable, consisting, for instance, as shown, of hooks p formed on the side wires and loops or eyes o', Fig. 5, or q, Fig. 1, formed on the globe plate, so that the latter can be detached from the wires, when 85 desired.

When the globe plate rests upon the shoulder of the burner cone, in the construction represented in Fig. 1, only the extreme lower ends of the wires project into the hood, 90 while the main portions of the wires are located outside of the hood, while in the construction represented in Fig. 5 the side wires are located entirely outside of the hood. In either case, the wires do not obstruct the interior surface of the hood and all parts of the latter can be easily reached for cleaning. If desired, the globe plate can be detached from the side wires and removed for giving more 95 convenient access to the parts which lie in 100 rear of the burner.

The vertically movable bell or canopy, the side wires and the globe plate constitute a globe holding frame which is vertically movable in the rigid lantern frame, the latter 105 comprising the air tubes, the central tube and the base portion containing the oil pot.

I claim as my invention:

1. The combination with a tubular lantern frame provided with a reflecting hood, of a 110

globe holding frame which is vertically movable in the lantern frame and which comprises side members arranged outside of the hood and a bottom member, upon which the globe is supported, arranged within the hood and connected with the lower ends of the side members, substantially as set forth.

2. The combination with a tubular lantern frame and a reflecting hood secured in the same and provided with side openings, of a globe-holding frame which is vertically movable in said lantern frame and comprises side members which are arranged outside of the hood, a globe plate which is arranged within the hood, and devices connecting the side members with the globe plate and extending through the side opening of the hood, substantially as set forth.

3. The combination with a tubular lantern frame and a reflecting hood secured in the same and provided with side openings, of a globe holding frame which is vertically movable in the lantern frame and which com-

prises side members arranged outside of said hood and having their lower portions extending inwardly through the side openings of the hood, and a bottom member upon which the globe is supported and which is arranged within the hood, substantially as set forth. 25

4. The combination with a tubular lantern frame and a reflecting hood secured in the same, of a globe holding frame which is vertically movable in the lantern frame and which comprises side members arranged outside of the hood, a bottom member upon which the globe is supported and which is arranged within the hood, and detachable means connecting the side members with the bottom member, substantially as set forth. 30 35

Witness my hand in the presence of two 40 subscribing witnesses.

CHARLES BERGERER.
